(57) CLAIM

The ornamental design for a package for nail fashion articles, as shown and described.

DESCRIPTION

FIG. 1 is a front perspective view of our new package for nail fashion articles design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is an exploded front perspective view thereof in a first arrangement;

FIG. 9 is an exploded front perspective view thereof in a second arrangement;

FIG. 10 is an exploded front perspective view thereof in a third arrangement; and,

FIG. 11 is an exploded front perspective view thereof in a fourth arrangement.

The broken dash lines shown in the drawing views illustrate portions of the package for nail fashion articles that form no part of the claimed design.
